UNITED STATES PATENT OFFICE.

WYLIE E. MURRAY AND HARRY A. LEACH, OF ST. LOUIS, MISSOURI.

LOCKING-VALVE.

1,172,823.

Specification of Letters Patent. Patented Feb. 22, 1916.

Application filed December 8, 1913. Serial No. 805,370.

To all whom it may concern:

Be it known that we, WYLIE E. MURRAY and HARRY A. LEACH, citizens of the United States, and residents of St. Louis, Missouri, 5 have invented certain new and useful Improvements in Locking-Valves, of which the following is a specification.

Our invention relates to improvements in locking valves, and has for its object 10 a valve with a locking means for controlling the passage of the fuel supply from the supply tank to the engine.

A further object of our invention is to provide a locking valve designed to be located on a fuel supply pipe and preferably placed between the fuel tank and the carbureter from which the fuel is fed into an internal combustion engine, and the device is applicable for automobile engines, motor- 20 boats and the like, and the purpose of the valve is to guard against the stealing of the vehicle when the machine is left idle on the siding and also from destruction by fire in the event of accident.

25 Figure 1, is a view of an internal combustion engine showing our device in relative position. Fig. 2, is a side view of the device with portions thereof in section. Fig. 3, is a view of the combination mechanism, 30 the cover having been removed. Fig. 4, is a top plan view of the cover and the combination dial. Fig. 5, is a detail sectional view of a portion of the connecting shaft or rod made use of on the device as employed 35 on automobiles. Fig. 6, is a detail plan view of one of the locking disks which forms a part of the combination mechanism.

Referring to the drawings in detail 7 indicates an ordinary internal combustion 40 engine, such as used for automobiles and the like; 8 the carbureter, and 9 the fuel supply pipe which leads to the fuel supply tank wherever located on an automobile, motor-boat or the like.

45 On the fuel supply pipe 9, we place our improved locking valve, the same being located preferably close to the carbureter and in such position that access can be had to the same when the hood of the vehicle is raised. The locking valve consists of an ordinary valve 11, properly coupled in position to the supply pipe, and said valve is rigidly mounted on a plate 10; the valve stem which controls the valve mechanism 50 being rigidly secured to the tumblers 12, which are mounted on the opposite side of

said plate 10, and these tumblers may be constructed sectional as shown. Upon the plate 10, are also mounted locking disks 13, 14, and 15, which are constructed circular 60 in form, each being provided with a recess in its periphery in which is designed to be seated a tooth or projection formed on the tumblers 12.

The tumblers 12, are arranged to be held 65 in locked position by a spring 16, and the tendency and normal tension of said spring is to force the projecting end or tooth of the tumblers into the notch or recess of the tumbler disks when all of the notches or 70 recesses are in proper alignment and beneath the projections. The position assumed by the valve when open being illustrated by solid lines in Fig. 3, and the close position by dotted lines same figure. Upon the plate 75 10, is mounted a cover 17, and upon this cover is mounted a combination disk 18; the movement and connection of the same being hereinafter described.

On the shaft 19, which projects through 80 the entire mechanism and plate 10, and which is provided with a head connecting with the opposite side of said plate is firmly secured the locking disk 13, and on the outer projecting end of said shaft is located 85 a universal coupling 20, consisting of a bifurcated portion 21, which is held rigid on said shaft by means of the cross pin 22. The inner end of the bifurcated portion 21, is provided with two projecting pins 24, 90 which are designed to fit into two openings 23, formed in the combination disk 18, and by which said disk can be rotated when the bifurcated member 21, is manipulated.

Connected to the bifurcated portion 21, is 95 a bifurcated portion 25, which constitutes a portion of the universal joint which joint is of the ordinary universal construction; and to the portion 25, is connected a tube or rod 26, held in position by means of a 100 cotter pin or the like 27. This tube or rod 26, extends into a second tube 28, which is provided with two elongated slots 29; and into these slots projects a pin 30, which is passed through the inner tube and which 105 will allow a certain limit of extension and at the same time permit each tube to simultaneously rotate when the same is manipulated, in order to turn the combination disk.

The upper end of the outer tube 28, is also 110 provided with a universal joint or coupling 31, and to this coupling is attached a short

shaft 32, provided at its upper end with a similar or duplicate combination disk 33, and a disk manipulating knob 34. This combination disk 33, is mounted on a bracket 35, which is secured to the dash board of the vehicle. And by the manipulation of the disk from that point will simultaneously turn the rods or tubes and the combination disk and the mechanism located on and in the casing supported over the valve.

The valve itself is provided with a cap 36, which is firmly secured to the plate 10. The tumbler disk 13, which as before stated is firmly secured to the shaft 19; on the inner face of said disk, is located a pin 13^a, this pin is so arranged as to contact with a similar pin 14^a located on the center tumbler disk 14, and which when contacted with will turn the disk 14, which is loosely mounted on the shaft 19, and on the opposite side of the disk 14, is a similar pin 14^b which is designed to contact with a like pin 15^a located on the face of the tumbler disk 15, which disk is also loosely mounted on the shaft. These two loosely mounted disks are so constructed as to retain their set position while the shaft 19, is permitted to rotate in either direction; and in this manner the recesses in the periphery of each of said disks are brought in proper alignment by the manipulation of the shaft in order that the projections on the tumblers 12, may seat themselves therein and open the passageway of the valve so that the fluid may enter from the tank into the carburetor.

It will be observed that the disk 13, as shown in Fig. 3, has that portion of its periphery which leads to the base of the recess rounded. The object of this is, that when desiring to lock the valve and raise the tumblers out of the recesses, the shaft when turned to the right, as viewing Fig. 3, will cause the rounded portion to elevate the tumblers 12, so as to permit them to ride on the periphery. When this is done and by twirling the combination disk the tumbler disks 13, 14, and 15, will rotate and the recesses therein become staggered.

The construction of the tumblers and tumbler disks is simple as the tumbler 12, is pivoted to the valve stem and controlled by the action of the spring 16. The tumbler disks 13, 14, and 15 are mounted on the shaft 19, the tumbler disk 13, being fixed thereto while the disks 14 and 15, are mounted loosely on said shaft and each provided with pins on their faces arranged to contact with each other, so by the rotation of the shaft in the manner of the ordinary combination lock operation brings the disks to their proper position, first one being brought in its proper location and then the next and so on in accordance with the numbers designated on the dial 18.

The operation of our invention is as follows: After the device has been placed in position on the pipe and when desiring to open the valve so that the fluid has free passage from the tank to the carburetor, the dial is operated to the proper numbers bringing the disks 13, 14, and 15 in such position that the recesses located therein are in proper alignment with the tooth or projection of the tumbler 12. When in such alignment the spring 16 forces the tumbler into a position as shown by solid lines in Fig. 3, and when in such position the device is located and prevented from shifting by the shaking or jarring of the vehicle on which said device is located.

In order to cut-off the valve in order to stop the flow of the fluid, the knob 34, is turned toward the right bringing the rounded portion on the periphery of the disk 13, in contact with the projection or tooth of the tumbler 12, raising the same in a position as shown by dotted lines in Fig. 3; and by continuing the rotation the recesses in the several tumbler disks become staggered or out of alignment, holding the tumbler 12 in such elevated position at the same time keeping the valve closed.

Having fully described our invention what we claim is:

1. A locking valve for internal combustion engines, comprising a center base plate, a housing located on each side thereof, a valve mounted on one side of said base plate and to one side of the center, a tumbler mechanism mounted on the opposite side of said base plate and secured to the stem of said valve for controlling the valve action and a combination mechanism controlling the tumbler mechanism, substantially as specified.

2. A locking valve for internal combustion engines, comprising a base plate, a valve mounted on one side of said base plate and to one side of the center, a tumbler mechanism mounted on the opposite side of the base plate, a valve stem protruding through the base plate connecting the valve and tumbler mechanism, a housing incasing the valve and a housing incasing the tumbler mechanism, substantially as specified.

3. A locking valve for internal combustion engines comprising a base plate, a valve located on one side of said base plate, a valve stem protruding through said base plate, an oscillating tumbler mounted on the valve stem, a spring controlling the same and rotating locking disks located centrally on the base plate and contacting with the oscillating tumbler, substantially as specified.

4. A locking valve for internal combustion engines comprising a valve located on the fuel supply pipe near the carburetor, an oscillating tumbler means for operating the valve for controlling the passage of the fuel

through said pipe, a spring for holding the valve in set position when the fuel is cut-off; rotating locking disks centrally located, a housing incasing the same, a combination mechanism mounted on said housing and operating the rotating locking disks which controls the movement of the oscillating tumbler, substantially as specified.

5. A device of the class described comprising a base plate, a valve located to one side thereof, a fuel supply pipe to which said valve is connected, a tumbler operating said valve, a shaft supported in the base plate, two loose and one stationary tumbler disks 10 located on said shaft, a combination disk

supported on the housing and connected to the shaft, a second combination disk supported independently of the housing, and a connecting means located between the two combination disks whereby both disks are 20 operated simultaneously when opening or closing the valve, substantially as specified.

In testimony whereof, we have signed our names to this specification, in presence of two subscribing witnesses.
